United States Patent Office

Des. 212,917
Patented Dec. 10, 1968

212,917

CALCULATOR

Henry Dreyfuss, 500 Columbia St.,
South Pasadena, Calif. 91030

Filed Nov. 29, 1967, Ser. No. 9,579

Term of patent 3½ years

(Cl. D64—11)

FIG. 2.

FIG. 3.

FIG. 4.

FIG. 5.

FIG. 1 is a front perspective view of a calculator showing my new design;

FIG. 2 is a top view thereof;

FIG. 3 is a front elevational view thereof;

FIG. 4 is a right side elevational view thereof, the left side being similar in appearance; and

FIG. 5 is a rear elevational view thereof.

The essential features of the design reside in the portions shown in solid lines; conventional keys being shown in broken lines in FIGS. 1-4.

I claim:

The ornamental design for a calculator, substantially as shown and described.
